CLAIM

The ornamental design for a micro-mobility transit vehicle, as shown and described.

DESCRIPTION

FIG. 1 is a rear, left, and top perspective view of an embodiment of a micro-mobility transit vehicle embodying the new design;

FIG. 2 is a front, right, and bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines are shown for the purpose of illustrating portions of the micro-mobility transit vehicle and/or environmental matter and form no part of the claimed design.

(Continued)

The dot-dash broken lines define the bounds of the claimed design and form no part thereof. The oblique line shading is used to show retroreflective surfaces.
